C. DUBEAULT.
DIRECTION SIGNAL FOR AUTOMOBILES.
APPLICATION FILED AUG. 3, 1921.

1,426,281.

Patented Aug. 15, 1922.

UNITED STATES PATENT OFFICE.

CAMILLE DUBEAULT, OF CHICO, CALIFORNIA.

DIRECTION SIGNAL FOR AUTOMOBILES.

1,426,281.

Specification of Letters Patent. Patented Aug. 15, 1922.

Application filed August 3, 1921. Serial No. 489,532.

To all whom it may concern:

Be it known that I, CAMILLE DUBEAULT, a citizen of the United States, residing at Chico, county of Butte, State of California, 5 have invented certain new and useful Improvements in Direction Signals for Automobiles; and I do declare the following to be a full, clear, and exact description of the same, reference being had to the accompanying drawings, and to the characters of reference marked thereon, which form a part of this application.

This invention relates to improvements in direction signals for automobiles, the principal object being to provide a mechanical signal member, to be used instead of the human hand as is now commonly done, which may be in the form of a single unit member, readily attached to the windshield 20 of the car in a few seconds' time.

Another object is to provide a means whereby the signal may be set by hand in any one of the various positions required by law, depending on the direction of movement to be taken by the driver of the car, which position will be automatically maintained even though the operator's hand is withdrawn.

A third object is to provide a device of 30 this character the signal arm of which is intended to show both in the day time and at night, and so constructed that any member apt to break may be easily and quickly replaced.

35 A further object of the invention is to produce a simple and inexpensive device and yet one which will be exceedingly effective for the purposes which it is designed.

These objects I accomplish by means of 40 such structure and relative arrangement of parts as will fully appear by a perusal of the following specification and claims.

In the drawings similar characters of reference indicate corresponding parts in the 45 several views.

Fig. 1 is a perspective outline of a portion of an automobile, showing my improved signal installed thereon.

Fig. 2 is a detached top plan view of the 50 signal member itself, showing particularly the signal operating mechanism.

Fig. 3 is a fragmentary side view, partly in section, of the outer end of the operating arm.

55 Fig. 4 is a side or face view of the signal member detached.

Referring now more particularly to the characters of reference on the drawings, the numeral 1 denotes a suitable form of clamp, adapted to be removably connected to one of the vertical frames 2 of the windshield or similar member of a motor vehicle.

Mounted on the clamp in a horizontal plane and arranged for a limited amount of swivel movement in a vertical plane relative to the clamp, and adapted to be secured in any such position, is a cylindrical tube or sleeve 3 provided around its forward edge with a plurality of notches 4.

Turnably and slidably mounted in the 70 tube 3 is a shaft or arm 5 preferably hollow, on the rear end of which is a handle member 6 of any suitable form.

The forward end of the shaft, beyond the 75 sleeve 3 is provided with a cross-pin 7, arranged to seat in any opposed pair of the notches 4 and normally held seated therein by a spring 8 secured to the clamp and acting on the shaft to move it to the rear.

Beyond the pin 7 the shaft 5 has a bent 80 arm 9, preferably at a right angle, on the outer end of which is a signal arm 10. This member comprises a pair of spaced and inwardly grooved sheet-metal edge-members 11, coming together at their outer ends and 85 adapted at their outer ends to rest on the edge of and to be secured onto a disc 13 screwed onto the outer end of the arm 9 by means of screws 13a.

Held by the grooved members 11 and 90 curved outwardly from one end to the other so as to enclose a substantially oval shaped area are translucent panes 14 preferably of celluloid or similar material, and suitably colored if desired, the ends of which adjacent the ends 12 of the members 11 are supported and held by stamped sheet-metal members 15, which rest against and are likewise screwed onto the disc 13.

An electric light 16 is socketed in the outer 100 end of the arm 9, the wires 17 for which pass through the hollow members 8 and 9 until they are in a convenient plane to be passed out and connected to the lighting circuit of the car.

By means of the construction just described, by merely unscrewing the disc 13, the signal arm as a whole is removed from the arm 9, exposing the lamp 17, while by unscrewing the members 11 and 15, the members 14 may 110 be withdrawn and replaced if necessary.

In the operation of the signal as a whole,

it is only necessary to impart a rotative movement to the handle 6 to set the signal 10 in any desired angular position. Such a movement will cause the pin 7 to raise out 5 of one set of notches, the spring 8 yielding at the same time to permit of this taking place. After the handle has been turned to set the signal at the angle desired, it may be released, the action of said spring drawing 10 the shaft rearwardly and causing the pin 7 to engage a set of notches corresponding to the new position of the handle, these notches being so shaped that the pin will be drawn into place therein even if the position 15 to which the signal has been moved by the hand does not accurately correspond to the position of the notches with respect to the pin.

From the foregoing description it will be 20 readily seen that I have produced such a device as substantially fulfills the objects of the invention as set forth herein.

While this specification sets forth in detail the present and preferred construction 25 of the device, still in practice such deviations from such detail may be resorted to as do not form a departure from the spirit of the invention, as defined by the appended claims.

Having thus described my invention, what 30 I claim as new and useful and desire to secure by Letters Patent, is:—

1. A direction signal including a substantially horizontal sleeve adapted to be se-

cured to a windshield, a shaft slidably and 35 turnably mounted in the sleeve, a handle on the shaft to the rear of the sleeve, a right-angle bend on the shaft ahead of the sleeve, notches cut in the sleeve at that end thereof, a member on the corresponding end of the 40 shaft for engagement with any of said notches, and spring means acting on the shaft to hold said member in engagement with any of said notches at a time.

2. A direction signal including a substantially horizontal sleeve adapted to be secured to a windshield, a shaft slidably and turnably mounted in the sleeve, a handle on the shaft to the rear of the sleeve, an integrally formed right-angle bend on the shaft 50 ahead of the sleeve, and a signal member secured onto the end of said bent portion and extending as a continuation thereof.

3. In a direction signal, an arm, a lamp mounted in the outer end thereof, and a hollow signal member, such member comprising a pair of spaced and grooved edge members connected together at their outer ends, a pair of outwardly curved translucent panes held by the edge members, opposed metal 60 members for holding the inner ends of said translucent members in place, and a disc screwed onto the outer end of the arm and to which the adjacent ends of the pane-holding members are removably secured. 65

In testimony whereof I affix my signature.

CAMILLE DUBEAULT.
